UNITED STATES PATENT OFFICE.

IVERT LARSEN, OF CHICAGO, ILLINOIS, ASSIGNOR OF ONE-HALF TO
ROBERT G. ARMSTRONG, OF CHICAGO, ILLINOIS.

CONNECTING DEVICE.

SPECIFICATION forming part of Letters Patent No. 699,398, dated May 6, 1902.

Application filed August 21, 1901. Serial No. 72,745. (No model.)

To all whom it may concern:

Be it known that I, IVERT LARSEN, of Chicago, in the county of Cook and State of Illinois, have invented certain new and useful 5 Improvements in Connecting Devices; and I do hereby declare that the following is a full, clear, and exact description thereof, reference being had to the accompanying drawings, and to the letters of reference marked thereon, 10 which form a part of this specification.

This invention relates to an improved connecting device for detachably connecting two separable parts end to end. The device is herein shown as applied to join the two ends 15 of a divided breast-strap for horse-harness used as a part of fire-department equipment and intended for the light harness of a chief's or other officer's wagon or buggy, and the device is constructed to permit the two parts of 20 the strap to be quickly joined or connected when placing the harness on the horse, as is necessary in such equipment.

The invention consists in the matters hereinafter set forth, and more particularly pointed 25 out in the appended claims.

Figure 1 is a perspective view of a fragment of a harness breast-strap, showing my improved connecting device applied to connect the same. Fig. 2 is a plan view, partly 30 broken away, of one of the interlocking members of the connecting device and the end of the strap to which it is attached. Fig. 3 is a top plan view of the other interlocking member of the device and its associated end of the 35 strap. Fig. 4 is a longitudinal section taken through the connecting device and the strap, showing the parts of the device in their interlocked positions. Fig. 5 is a cross-section taken on line 5-5 of Fig. 4. Fig. 6 is a longitudinal section of a modified form of attaching 40 devices and the parts of the strap to which they are attached. Fig. 7 is a similar view of a further modification.

As shown in the drawings, A A designate 45 two parts of a divided breast-strap adapted to be joined by my improved connecting device.

B B' designate as a whole the two interlocking parts or members of the device. 50 One of said members is provided with a loop

which extends beyond the part of the strap to which it is attached, and the other member is provided with a locking-plate, which is adapted to laterally enter the loop of the other member and is formed at its outer margin to have bearing engagement with the outer end or part of the loop and at its inner margin with a projection adapted to detachably interlock with a projection carried by the other member, one of said projections being movable and spring-pressed to permit said members to be locked and unlocked, said projections when in their interlocked positions preventing detachment of the parts of the strap and holding them firmly together. The yielding locking projection may be made a part of either of the interlocking members. In Figs. 1 to 6 the said yielding projection is made a part of the looped member, while in Fig. 7 it forms a part of the locking-plate member.

First referring to the construction shown in Figs. 1 to 5, inclusive, B designates the locking-plate, and C designates as a whole the loop which said plate enters and with which it interlocks. The loop consists of two 75 side members c c and a transverse end member c', which is rounded or cylindric. The locking-plate is provided with a base or flange B', by which it is attached to the strap, and the loop is formed on a plate C', said parts 80 B' C' being attached to the ends of the strap by rivets or like fastening means and are flush at their adjacent ends with the inner ends of the strap. The loop projects outwardly beyond the end of the strap to which 85 it is attached, and the locking-plate is adapted to laterally enter said loop from the inner side thereof, or the side toward the strap.

The inner margin of the plate B is provided with an angular notch, forming thereon a locking projection which forms a locking-shoulder b, which faces inward or toward the strap and is adapted for interlocking engagement with a projection on the other member of the device. The opposite or outer margin of said 90 plate is provided with a rearwardly-opening curved notch or recess b', adapted to fit over and have bearing engagement with the end portion c' of the loop. Said notch forms at the extreme end of the plate a prong b². The 100

interlocking projection of the loop C, which engages the shoulder b, is formed on the inner end of an endwise-reciprocating bolt D, which projects at its inner end into the loop and is contained in a barrel or tubular casing C², formed integral with the plate C' and loop C.

D' designates a spiral spring which is interposed between the outer end of said bolt and the closed end of the barrel, and said spring 10 D' tends to hold the inner end of the bolt projected into the loop. The inner end of said bolt is provided with a projecting tooth d, Fig. 2, having an outwardly-facing bearing-surface, which is adapted to engage the shoulder b when the parts are locked together 15 in the manner shown in Fig. 4.

When the parts are to be locked together, the prong b² of the locking-plate is inserted laterally into the loop from the inner side 20 thereof, with the curved notch b' of said plate engaging the rounded end of the loop. The parts are brought into their interlocked positions by turning or rotating one part with respect to the other, the end c' of the loop constituting a pivot about which the locking 25 plate is turned. The end face of the bolt D is by this movement carried over the end face of the plate B until it is brought past the shoulder b of said plate, when said plunger 30 is forced inwardly or toward said plate B by the spring D', and contact of the lateral bearing-surfaces on said tooth and shoulder prevents backward movement of the member in a manner to unlock the same. In order to facilitate the movement of the end of the bolt into 35 engagement with the shoulder b, said plate is provided between the prong b² and the shoulder b with a curved surface b³, which when the plate enters the loop engages the oblique outer end d' of the plunger, this construction causing 40 the plunger to be readily forced outwardly or backwardly until the tooth passes the shoulder on the plate. In order to retract said plunger D to release the same from the shoulder of the locking-plate, said plunger is provided 45 with a transverse actuating-pin D², which is extended downwardly through a slot d² in the barrel in position for manual engagement. Desirably said actuating-pin also 50 extends through and beyond the other side of the plunger and engages a guide-slot d³ in the other side of the barrel. When the parts are in their locked positions, with the shoulder b engaged by the end of the plunger, as 55 seen in Fig. 4, the engagement of the bolt with the shoulder prevents movement in a direction to detach or unlock the parts. Moreover, said curved notch b' fits closely against the rounded part c' of the loop, so that when 60 the parts are locked the said notch b' by its engagement with the said part c' holds the extremity of the loop from inward or outward movement on the plate. It will be noted that when the parts are in their interlocked position, as shown in Fig. 4, the margins of the curved notch b' fit closely against the rounded outer end c' of the loop on approximately

one-half its circumference and that the ends of the plate C' and flange B' abut against each other. The engagement of the shoulder b with the plunger and of the inner margin of the notch b' of the locking-plate with the rounded end c' of the loop prevents movement of the members in a direction to unlock the same, and the abutting engagement of the ends of the plate C' and flange B' with each other and of the outer half of the margin of the notch b' with the outer rounded part of the loop prevents movement of said members in an opposite direction to carry the same past 80 their locking positions. Said members when interlocked, therefore, are firmly supported against lateral or horizontal movement tending to cause displacement or rattling of the parts. The locking-plate is made of such 85 width as to entirely fill the loop and have contact with both side margins thereof, and this construction, together with the abutting relation of the plate and flange C' B', prevents vertical flexure of the strap, so that 90 there is no tendency of the strap to sag at the line of junction thereof.

In the construction shown in Figs. 1 to 5, inclusive, it will be noted that the loop projects obliquely outwardly or away from the 95 strap, the purpose of this arrangement being to facilitate the entrance of a drilling-tool to form the bore of the barrel D. This arrangement of the loop locates the outer end thereof of such distance from the attaching plate 100 and flange of the members that the abutting margins of said plate and flange constitute stops, which prevent the members being moved past their locking positions in the manner above stated; this result being 105 due to the angular relation of the outer end of the loop with respect to the line of junction of the plate and flange.

In Fig. 6 I have shown a construction wherein in the loop is approximately parallel with the attaching plate and flange of the members and in which the bore of the barrel is originally made open at its outer end, so that the drilling-tool which forms the bore of the barrel is inserted into the end of the barrel remote from the loop. In said construction, F designates the loop; F', its attaching-plate; G, a bolt located in a barrel F², formed integral with the loop and attaching-plate, and G' a spring interposed between the closed end of the barrel and the outer end of the bolt. The loop is made substantially like the loop C, before described, with the exception that it is located in substantial alignment with the barrel F². The arms of the loop are 125 connected by a transverse rounded-end member f, as before. H designates a locking-plate which enters said loop laterally from the inside thereof and is attached to the strap by a flange H' and is provided at its outer margin with a rearwardly-opening notch h, which fits over the rounded end of the loop, and at its inner margin with a shoulder h', adapted for interlocking engagement with a tooth g.

on the inner end of the bolt. As before stated, the bore of the barrel G is drilled from the outer end thereof, and said outer end of the barrel is closed by a screw-plug G², which 5 constitutes the closed end of the barrel. The inner margins of the side arms of the loop F bear against the outer face of the locking-plate flange, as shown in dotted lines in Fig. 6, and constitute a lock to prevent the members 10 swinging past their locking positions, the abutting relation of the plate and flange F' H', respectively, of said members not being depended upon to hold the parts rigidly in alinement, as in the construction before described. 15

In Fig. 7 I have shown a modification wherein the yielding locking projection or the bolt is mounted in the locking-plate member. In said figure, I designates the loop having the 20 rounded outer end i and attached to or formed on an attaching-plate I', which is thickened to give strength thereto. Said loop projects obliquely away from its attaching-plate, as in the construction first described. J designates a locking-plate provided with an attaching-flange J'. Formed on said flange J' and between the strap and locking-plate is a 25 barrel J², containing a bolt J³, which extends at its inside or beyond the inner margin of the locking-plate and is provided at its inner end with a tooth j. The plate I is provided 30 inside the loop with a shoulder i', which is adapted to be engaged by the tooth on the inner end of the bolt. The locking-plate J is provided with a rearwardly-opening curved 35 notch or recess j', which engages the rounded end i of the loop in the same manner as in the previously-described construction. The inner end of the bolt J³ is beveled or made oblique 40 on the advance side thereof or that which strikes the plate J when entering the loop, so as to effect the retraction of the bolt past the edge of the plate I when the locking-plate is swung into place. The bolt is held in its outermost position by means of a spiral spring 45 J⁴, interposed between the closed end of the barrel and the outer end of the plunger and is adapted to be retracted to release the plunger from the projection i' by means of a transverse pin J⁵, which passes outwardly through 50 a slot in the wall of the barrel. In this construction the abutting ends of the members constitute stops to prevent the swinging of said members past their locking positions in 55 the general manner of the construction shown in Figs. 1 to 5, inclusive.

The manner of using both of the forms shown in Figs. 5 and 6 is obviously the same as that of the construction first described and 60 need not again be stated.

It is obvious that changes may be made in the structural details illustrated without departing from the spirit of the invention, and I do not wish to be limited to such details 65 excepting as hereinafter made the subject of specific claims. It is furthermore obvious that the device described may be applied to

various uses for rigidly joining or connecting parts in the general manner set forth.

I claim as my invention—

1. The combination with two interlocking members one embracing a loop and the other a locking-plate, said plate being provided on its outer margin with a rearwardly-opening notch adapted to engage the end of said loop and at its inner margin with a projection which is adapted to be interlocked with a projection carried by the other member, one of the said projections being spring-pressed, to permit said members to be locked and unlocked. 70 75 80

2. The combination with two interlocking members one embracing a loop and the other a locking-plate, said plate being provided on its outer margin with a rearwardly-opening notch adapted to engage the end of said loop and at its inner margin with a projection which is adapted to be interlocked with a projection carried by the other member, one of the 85 90 95 said projections being spring-pressed to permit said members to be locked and unlocked, said members having abutting parts which are brought into contact when said members are locked to prevent said members being moved to past their locking positions.

3. The combination with two interlocking members one embracing a loop and the other a locking-plate adapted to enter said loop, said locking-plate being made of such width as to engage both side members of the loop, said plate being provided at its outer margin 100 with a rearwardly-opening notch which engages the end of the loop and at its inner margin with a projection which is adapted for interlocking engagement with a projection carried by the other member, one of said projections being spring-pressed to permit said members to be locked and unlocked. 105 110

4. The combination with two interlocking members one embracing a loop and the other a locking-plate adapted to enter said loop, 110 said locking-plate being made of such width as to engage both side members of the loop, said locking-plate being provided on its outer margin with a rearwardly-opening notch which engages the outer end of the loop and 115 on its inner margin with a projection adapted for interlocking engagement with a projection carried by the other member, one of said interlocking parts being spring-pressed to permit the members to be locked and unlocked, 120 and parts on said members which are in contact when said members are locked to prevent said members being moved beyond their locking positions. 125

5. The combination with two interlocking members one embracing a loop and the other a locking-plate adapted to enter said loop, said plate being provided on its outer margin with a rearwardly-opening notch adapted to engage the end of the loop, one of said parts 130 being provided with a barrel in alinement therewith, an endwise-reciprocating plunger sliding in said barrel, and a spring interposed between the outer end of said plunger and the

end of the barrel, and the other part being provided with a shoulder adapted for interlocking engagement with the plunger.

6. The combination with two interlocking members one embracing a loop and the other a locking-plate adapted to enter said loop, said plate being provided on its outer margin with a rearwardly-opening notch adapted to engage the end of the loop, one of said parts being provided with a barrel, an endwise-reciprocating spring-pressed plunger in said barrel and a spring interposed between the outer end of said plunger and the end of the barrel, and the other part being provided 15 with a shoulder adapted to have interlocking engagement with the plunger, and means for moving said plunger endwise comprising a pin which enters a transverse aperture in said plunger and extends outwardly through 20 a slot in the wall of the barrel.

7. The combination with two interlocking members one embracing a loop and the other a locking-plate, said plate being provided in its outer margin with a rearwardly-opening notch which engages the outer end of the 25 loop, and a spring-pressed plunger on the loop member the inner end of which enters said loop, said locking-plate being provided on its inner margin with a shoulder adapted to engage the plunger to hold the members in 30 their locked positions.

In testimony that I claim the foregoing as my invention I affix my signature, in presence of two witnesses, this 17th day of August, A. D. 1901.

IVERT LARSEN.
